UNITED STATES PATENT OFFICE.

JOHN SELLERS BANCROFT AND MAURITZ C. INDAHL, OF PHILADELPHIA, PENNSYLVANIA, ASSIGNORS TO LANSTON MONOTYPE MACHINE COMPANY, OF PHILADELPHIA, PENNSYLVANIA, A CORPORATION OF VIRGINIA.

TYPE-MOLD.

1,094,625.

Specification of Letters Patent. Patented Apr. 28, 1914.

Application filed December 23, 1912. Serial No. 738,282.

To all whom it may concern:

Be it known that we, JOHN SELLERS BANCROFT and MAURITZ C. INDAHL, of Philadelphia, in the county of Philadelphia and 5 State of Pennsylvania, have invented certain new and useful Improvements in Type-Molds; and we do hereby declare the following to be a full, clear, and exact description of the same, reference being had to the 10 accompanying drawings, forming a part of this specification, and to the figures and letters of reference marked thereon.

This invention relates to improvements in what are known as low quad type molds or 15 such as are adapted to produce both type and spaces or quads, the two latter either shoulder high or shorter.

Molds of this class, as heretofore constructed, have been provided with a cut-off 20 for the upper or character end of the mold cavity, usually in the form of an independently movable section of the mold blade or dimensioning and ejecting member, the latter being formed in two longitudinal sections, 25 superposed the one upon the other, whereof the lower or dimensioning member is connected with the mold adjusting devices, while the upper or cut off member is controlled by selective adjusting means 30 whereby it is either projected beyond the lower section, to close the end of the mold cavity, or sustained in register with the operative end of the lower section, to form a continuation of the side wall of the mold 35 cavity. This arrangement permits the production of two lengths of quads, one shoulder high, resulting from the seating of a blank matrix on the mold with the two mold blade sections alined and subject to the mold 40 adjusting devices, and the other shorter by the thickness of the upper or cut off section of the mold blade, resulting from the projection of the latter into the end of the mold cavity so as to form an end wall therein 45 against which the cast is made. These molds are specially designed for use in connection with automatic type casting and composing machines equipped with a series of matrices 50 adapted for selective individual application to the end of the mold after the manner disclosed in Patent No. 625,998 of May 30, 1899.

In the case of printing type the height of the character above the shoulder is deter-

mined by the depth of drive, *i. e.* the depth 55 of the countersunk depression in the matrix, and in commercial matrices this amounts to .03 in.; hence it follows that the difference between character type and spaces or high quads, such as result from the seating of a 60 blank matrix in the mold with the faces of the two mold blade sections in alinement, is but .03 in.

Under some circumstances, as when a considerable interval is occupied by quads, this 65 difference is insufficient to prevent smearing by the transfer of ink from the quads to the surface upon which the impression is taken, hence the introduction of the low quad mold whereby the quads are formed 70 of less than shoulder height. It has been found in practice, however, that a length of quad best suited for stereotyping is not so well adapted for other classes of work, such as electrotyping, owing to the fact that the 75 latter requires less depth than the former for the white, the deeper cavities produced by the low quads tending to retain and prevent or retard the drawing of the softer or wax like impression material commonly 80 employed in this process. Moreover, although the cut-off feature of the low quad mold is applicable to the interword spaces as well as the quads, it is not commonly so used for stereotype work on account of the 85 relatively deep and narrow cavity produced thereby which interferes with the proper withdrawal of the flong.

Now it is the object of the present invention to furnish a mold capable of producing, selectively, spaces and quads of three or more different heights and adapted for use in composed matter designed either for direct printing, stereotyping or electrotyping, to which end the mold is equipped with 90 a mold blade formed of a series of superposed longitudinal sections and provided with means whereby the intermediate section or sections can at will be coupled and maintained with its end or casting face in 100 alinement with either adjacent section, the one under the control of the cut-off or low quad mechanism, and the other under the control of the mold dimensioning mechanism, the arrangement being such that when 105 the several sections are maintained with their casting faces in the same plane they form a side wall of the mold cavity for the

production of either character type or shoulder high spaces or quads; when the intermediate is held in register with the dimensioning section the upper or outer section 5 responding to the low quad mechanism may be projected to close the end of the mold cavity for the production of spaces or quads of a height shorter than shoulder height by the thickness of said cut off section; and 10 when the intermediate is coupled with said outer or cut off section the two will operate in response to the cut off controlling devices to close the end of the mold cavity for the production of spaces or quads of a height 15 less than shoulder high by an amount equal to the combined thicknesses of the two cut off sections.

In the accompanying drawings illustrating a preferred form of embodiment of the invention—Figure 1 is a perspective of the 20 mold. Fig. 2 is a partial section in the plane of the mold blade. Fig. 3 is a perspective view of the tri-sectional mold blade, the sections being disconnected and detached. Fig. 4 is a partial section transversely of the mold blade, in the plane of the through bolt. Fig. 5 is a perspective of the mold blade with the sections associated together, the upper section being in dotted lines. Fig. 6 is a partial section showing the arrangement of the adjustable top bearing for the mold blade. Fig. 7 is a diagrammatic view showing the arrangement of mold blade sections when subject to the 30 mold dimensioning mechanism. Fig. 8 is a similar view in which the upper section is controlled by the cut-off mechanism for closing the end of the mold. Fig. 9 is a similar view with two sections of the mold blade 35 under the control of the cut-off mechanism and the third section subject to the mold dimensioning mechanism.

Like letters of reference in the several figures indicate the same parts.

With the exceptions hereafter noted the mold illustrated is in all essential particulars the same as that disclosed in Patent No. 962,411, dated June 28, 1910, and is adapted for operation in connection with the 40 cut-off controlling and mold dimensioning mechanisms referred to therein.

It will suffice for purposes of identification to designate some of the principal elements of the prior patented structures such 45 as the base plate 1, side blocks 2, 3, cross block 4, main or lower mold blade section 5, upper or cut-off mold blade section 6, and its carrier 7, latch 8 pivoted in said carrier, and cross head 9.

According to the present invention there 50 is interposed between the lower and upper mold blade sections 5, 6, an intermediate, independently movable section 10 of the same width as the lower section and provided with a bearing 11 for the reception of

a suitable actuating device, the latter represented by a lever 12 pivotally supported on side block 3, and provided with a yielding retainer such as actuating spring 13, whose action on said lever can be reversed, as by 55 detachably connecting its outer end to either of two supports 14 located on relatively opposite sides of the pivot of said lever. The upper face of side block 3 is recessed for the accommodation of lever 12 so that no obstruction is presented to the free movement of the die case above the mold, said recess being bridged by a suitable cover plate, as shown. Lower section 5 is further provided with a gaging member 15 against which the 60 rear end of intermediate section 10 abuts when the inner or casting faces of the two sections are in register (see Figs. 5, 7 and 8) and the intermediate section 10 is also provided with a gaging surface 16 adapted 65 to contact with a complementary gaging member 17 on the carrier 7 when the casting face of the upper and intermediate sections 6, 10 are in register (Figs. 7 and 9).

The proportioning and arrangement of 70 the parts is such that when the carrier 7 is coupled with the mold dimensioning devices, as through the engagement of latch 8, intermediate section 10 will be clamped and held between gaging surfaces 15 and 17, with 75 its casting face or end in register with those of the lower and upper sections 5, 6, (Fig. 7) and the mold blade as a whole will be under the control of the dimensioning mechanism for casting character type or shoulder high spaces and quads, said dimensioning mechanism being represented in this case by the cross head 9 and cross pin 21 through which the adjusting and ejecting movements are transmitted to lower section 80 5. When, however, the cut off controlling devices, represented by lever 22, are brought into action, as by engagement with latch 8, the intermediate section 10 will be coupled with and respond to the action of either the 85 cut-off controlling or the mold dimensioning mechanism accordingly as its actuating devices are set in one direction or the other. Thus, if spring 13 is set to maintain the intermediate section 10 in contact with gaging member 15, the intermediate and lower sections will be maintained with their casting faces in register and subject to the action of the mold dimensioning devices while the upper section 6 alone responds to the 90 cut-off controlling mechanism (see Fig. 8) thereby producing a low quad or space, whose length, as compared with the normal or shoulder high space, is determined by the thickness of the upper section 6, and its width set-wise, by the conjoint action of the intermediate and lower sections. When, however, the action of spring 13 is reversed, so that it operates to hold intermediate section 10 in engagement with gaging member 130

17, the intermediate and upper sections will be advanced in unison in response to the cut-off controlling devices (see Fig. 9) and the produced space or quad will now be 5 shortened by an amount equal to the thickness of sections 6 and 10. Thus through the cut-off controlling mechanism and actuating devices of the intermediate section it becomes possible to selectively obtain from 10 the same mold spaces or quads of three different lengths and such as are best adapted for the purpose for which the composed matter is designed to be used, whether for direct printing, stereotyping, electrotyping 15 or other purposes.

It is of importance that the sections of the mold blade should be maintained in sufficiently close contact to prevent the entrance of molten metal into the joints between them 20 during the casting operation, which latter, as usual, is performed under considerable pressure. In the present instance this point is attained through pressure applied to the top guide 23 resting upon and engaging the 25 lower member of carrier 7 and transmitted through the top section 6 to intermediate section 10 and thence to lower section 5, whereby the latter is held to its seat in the mold blade channel.

30 Having thus described our invention, what we claim as new is:

1. A type mold provided with a casting chamber terminating at one end in a matrix seat and having one of its walls divided into 35 a series of independently movable sections superimposed one upon the other in planes substantially parallel with said matrix seat.

2. A type mold provided with a casting chamber terminating at one end in a matrix 40 seat, one wall of said chamber being formed by a mold blade, the latter comprising three independently movable sections superimposed in planes substantially parallel with said matrix seat.

45 3. A type mold provided with a three part mold blade, the sections whereof are superimposed and independently movable and with means for coupling the intermediate section with either adjacent section so as to partake 50 of enforced movements communicated to the latter.

55 4. A type mold provided with a movable mold blade comprising three superposed longitudinally movable independent sections, with means for coupling one outer section to a cut-off controlling mechanism, means for coupling the other outer section to

mold dimensioning mechanism, and means for selectively coupling the intermediate section to either outer section.

5. A type mold provided with a movable mold blade comprising three independent superposed longitudinal sections, with means for selectively coupling the intermediate section in gaged relation to either adjacent section, means for coupling one outer section with either a cut-off controlling or mold dimensioning mechanism and means for coupling the other outer section with a mold dimensioning mechanism.

6. A type mold provided with a tri-sectional mold-blade the intermediate section whereof is confined between opposed gaging surfaces on the outer sections, with means for selectively engaging the intermediate 75 section with the gaging member of either associated outer section so as to cause it to partake of the impressed movements communicated to said engaged section.

7. A type mold such as described, provided with side blocks and a movable cross block and in combination therewith a mold blade movable longitudinally between said side blocks and divided longitudinally into three superposed sections whereof the upper 85 and lower sections are provided with opposed gaging members between which a portion of the intermediate section is located, and reversible actuating means for maintaining the intermediate section in contact 90 with one or the other of said gaging members so that it will partake of the impressed movements thereof.

8. A type mold such as described including in combination side blocks; a movable cross block; a tri-sectional mold blade whereof the outer sections are equipped with opposed gaging members and the intermediate section is interposed between said gaging members; a lever connected to the intermediate section and provided with reversible actuating means; means for coupling one outer section of the mold blade to the mold dimensioning mechanism; and means for connecting the other outer mold section to 105 cut off controlling means, the same including a latch for coupling said outer section to the mold dimensioning mechanism.
